TOY FLAME THROWER GUN

Roy M. Bloom, 13 Harcourt Road, Scarsdale, N.Y.

Filed Mar. 13, 1963, Ser. No. 73,952

Term of patent 14 years

(Cl. D34—15)

FIG. 1.

FIG. 2.

FIG. 4. FIG. 5. FIG. 6. FIG. 7. FIG. 8.

FIGURE 1 is a side elevational view of a toy flame thrower gun showing my new design, the side opposite being a mirror image thereof;

FIGURE 2 is a plan view thereof;

FIGURE 3 is a bottom plan view;

FIGURE 4 is an end view as seen in the direction of line 4—4 in FIGURE 1;

FIGURE 5 is an end view as seen in the direction of line 5—5 in FIGURE 1;

FIGURE 6 is a cross sectional view taken along the line 6—6 in FIGURE 1; and

FIGURE 7 is a cross sectional view taken along the line 7—7 in FIGURE 1.

I claim:

The ornamental design for a toy flame thrower gun, as shown and described.
